UNITED STATES PATENT OFFICE

134,599

DESIGN FOR A RATIONING SPOON

Mary L. Beck, Chicago, Ill.

Application October 14, 1942, Serial No. 108,515

Term of patent 7 years

To all whom it may concern:

Be it known that I, Mary L. Beck, a citizen of the United States, residing at Chicago, in the county of Cook and State of Illinois, have invented a new, original, and ornamental Design for Rationing Spoons, of which the following is a specification, reference being had to the accompanying drawing forming part thereof.

Fig. 2 is a right-hand side view; and
Fig. 3 is a similar view, partly in section on the line 3—3 of Fig. 1.

I claim:

The ornamental design for a rationing spoon, as shown.

MARY L. BECK.
